UNITED STATES PATENT OFFICE

CHARLES H. CHASE, OF STONEHAM, MASSACHUSETTS, ASSIGNOR TO CARO CLOTH CORPORATION, OF CAROLINA, RHODE ISLAND, A CORPORATION OF DELAWARE

NEEDLING MACHINE

Application filed March 8, 1927. Serial No. 173,767.

My present invention relates to textile machinery, and more particularly to an improved needling machine for needling textile fibres through and incorporating the same therewith a base fabric and the fibres themselves.

In the application of Patrick H. Walsh, Serial No. 64,486, filed October 24, 1925, for textile fibres and method of making same, 10 there is disclosed and claimed, the improved method of incorporating textile fibres of a bat or web with a base fabric by needling the fibres of such bat or web through the base fabric and incorporating the same not only 15 with a base fabric but with the fibres themselves, and the present invention is to be considered an improved machine for carrying out the process claimed in the Walsh application, above referred to, and also for manufacturing the fabric therein claimed as an article.

In practicing the improved method and producing the improved article described and claimed in the Walsh application above referred to, considerable difficulty was experienced in forcing the fibres constituting the bat or web through the base fabric and produce an even texture in the resulting article. The present invention is designed to overcome the difficulties experienced in this regard, and in carrying out my invention, I have produced a needling device comprising essentially a plurality of needle holders each having more than one row of needles, and a plurality of such needle carrying devices are mounted in alinement with each other and for reciprocation in a vertical plane in any desired order. That is, there being a plurality of reciprocating needle holders, such 40 needle holders may be grouped in pairs or in combinations of any number desired, or may be each operated separately.

An important feature of the invention resides in the means whereby, in addition to the 45 reciprocatory movement in a vertical plane given to the needles and the needle holders, there is imparted thereto and simultaneously therewith, a reciprocatory movement in a horizontal plane, the speed of such movement being in timed relation to the feed of

the base fabric across the plane of movement of the needles.

Another important feature of my invention is the improved needle carrying head and in which the plurality of needles may be easily and accurately assembled. 55

In the accompanying drawings illustrating a preferred embodiment of my invention,

Fig. 1 is a plan view;

Fig. 2 is a side elevation partly in section;

Fig. 3 is a sectional side elevation;

Fig. 4 is an enlarged side elevation of the upper and of the left-hand end of the structure shown in Fig. 2;

Fig. 5 is a sectional elevation on the line 5—5 of Fig. 3;

Fig. 6 is a plan, and Fig. 7 a front elevation of one of the needling bars;

Fig. 8 is an end elevation of the needling bar;

Fig. 9 is a sectional elevation on the line 9—9 of Fig. 7;

Fig. 10 is a sectional plan view on the line 10—10 of Fig. 9;

Fig. 11 is a fragmentary plan view of the needling bar;

Fig. 12 is a perspective view of a portion of the clamping member of the needle bar, and

Fig. 13 is a fragmentary elevation of one of the needles.

Referring to the drawings, 10 designates base bars on which are formed uprights 11, there being uprights 11 for each base bar 10, 85 such uprights being spaced apart from each other, as clearly shown in Fig. 3, and are tied together at their top by bars 12. These bars 12 are secured to the uprights 11 by bolts 13. The base bars 10 are adapted to be secured to a framework 14 in any manner, preferably by means of bolts 15. The base bars 10 are spaced apart from each other and are held in spaced relation by the bolts 15, engaging through the same into the frame 90 14 and also by means of a channel plate or bar 16. Mounted on top of the channel bar 16, at each end thereof, are alined bearings 17, such bearings being secured in position on the channel bars 16 and the channel bars 100.

being secured in position on the cross bars 12 by bolts 18. Also mounted on the top of the channel bars 16, intermediate the bearings 17 and in alignment therewith, is a bearing 19. Rotatably mounted in the bearings 17 and 19, is a shaft 20 provided at each end with a hand wheel 21, and by means of which the shaft 20 may be rotated from either side of the machine. Adjacent each of the bearings 17 and secured to the shaft 20 are bevelled pinions 22, each pinion meshing with a bevel gear 23, which bevel gears 23 are secured to a shaft 24 rotatably mounted in bearings 25 formed on the cross bar 12. The lower end of the shafts 20 are threaded, as indicated at 26.

The uprights 11 are spaced apart from each other, as above described, and the opposing faces are parallel with each other and constitute vertically arranged spaced slides. In each pair of uprights 11 there is slidably mounted a framework 27, such framework comprising substantially a U-shaped member, as viewed in Fig. 3. On the cross portion of the U, is formed an inwardly extending member 28 carrying an internally threaded member 29 that engages with the threaded portion 26 of the screw 24. By rotating the shaft 20, the shafts 24 are rotated simultaneously and in the same direction and will, therefore, cause an upward or downward movement of the U-shaped frame 27 in the slides formed by the parallel faces of the uprights 11. Secured to the inner faces of the U-shaped members 27 are channel bars 30, and secured to the upper faces of the channel bars 30, which faces are in alignment with each other, are bearings 32, these bearings being in alignment with each other. Rotatably mounted in the bearings 32 is a multi-throw crank shaft 33. For convenience, the number of throws in the crank 33 is twelve, and also for convenience as well as for the purpose of balancing the device, such throws are arranged in pairs, and referring to Fig. 2, it will be noted that the two outer throws from each end are arranged in pairs, then the next two throws from each end, and finally the inner two pairs of throws 50 are so arranged. Secured to the bottom faces of the channel bars 30 by bolts 34, are cylindrical guides 35 and 36, the guides 35 being single guides, as shown in Fig. 2, while the other guides 36 are double guides. The guides 35 and 36 are in alignment with the throws of the crank shaft 33 and slidably mounted in each of the cylindrical guides is a cylindrical crosshead 37, each crosshead in turn being provided with a wrist pin 38. Rotatably mounted on each throw of the crank shaft 33 is one end of a connecting rod 39, the other end of each of the connecting rods 39 being rotatably mounted on the wrist pins 38. Obviously, therefore, from the above description, it will be apparent that a rotary

movement of the crank shaft 33 will, thru the connecting rods 39, cause a reciprocating movement in a vertical plane of the cylindrical crossheads 37. Rotatably mounted on each of the wrist pins 38 and depending downwardly therefrom, is a member 40. Referring to the description above with regard to the division or collection of the throws of the crank shaft in pairs, and referring now particularly to Fig. 5, it will be seen that the two outer connecting rods 39, form a pair and, therefore, that the wrist pins 38 of this pair reciprocate in unison and, therefore, and obviously, the members 40 will move in unison. Secured to the lower end of the members 40 is a needle bar 41, this needle bar being provided with a horizontally arranged and downwardly depending web 42, as clearly shown in Figs. 8 and 9. The manner in which the needles are carried by the bar 41 and the construction of such needles and the sub-carrying members therefore will be described in detail hereafter.

Secured to the multi-throw crank shaft 33, adjacent one end thereof, is a sprocket 43 which is in alignment with a sprocket 44 secured to a shaft 45, which shaft is rotatably mounted in bearings 46 secured to one of the channel bars 30 in any suitable manner. Over the sprockets 43 and 44 runs a sprocket chain 47 and by means of which power is transmitted from the multi-throw crank shaft 33 to the shaft 45. Secured to one end of the multi-throw crank shaft 33 is a sprocket 48, over which may pass a chain or other suitable means for transmitting power to the crank shaft 33 from any source of power. Secured to the lower end of the channel bar 30, to which is attached the bearings 46, are bearing brackets 49, such bearing brackets being provided with bearings 50. The bearings 50 are in alignment with each other, and rotatably mounted in such bearings is a shaft 51, this shaft lying parallel to but spaced apart from the multi-throw crank shaft 33. Secured to the shaft 45 at the end remote from the sprocket 44, is a sprocket 52, which is in alignment with a sprocket 53, secured to a shaft 51, and over the sprockets 52 and 53 runs a sprocket chain 54, and by means of which power is transmitted from the shaft 45 to the shaft 51. Secured to the shaft 51 in any suitable manner are cam plates 55, such cam plates being provided on one face thereof with a recessed cam race 56 of proper contour, as clearly shown in Fig. 3. There is a cam plate 55 for each of the downwardly depending members 40. Rotatably mounted on the shaft 51, adjacent each of the cam plates 55, is a bearing member 57, the outer contour of which is such that the opposite faces are parallel, as clearly shown in Fig. 3. Slidably mounted on the bearing members 57, is the U-shaped end 58 of a member 59, and such member 59

is provided with a cam roller 60, which engages in the cam race 56. Adjustably secured to each of the members 40, adjacent the lower end thereof, is a member 61, and to each member 61 is pivotally attached the end of one of the members 59. It is obvious from the above description that if the shaft 51 is rotated, that the members 59, by reason of the fact that the cam roller 60 engages in the cam race 56, will impart to the member 59 a reciprocating motion measured from left to right in Fig. 3, and that such motion will be imparted to the lower end of the member 40, which, as above described, is pivotally or rotatably mounted on the wrist pin 38. Therefore, any mechanism, as the needle bar or mechanism carried by such bar 41, will be given a reciprocating motion, which reciprocating motion would be in a substantially horizontal plane or in a cylinder of which the axis of the wrist pins 38 is a center, if the wrist pins 38 were stationary. Because of the fact, however, that the wrist pins 38 have a reciprocatory motion in a vertical plane, and such reciprocating motion takes place simultaneously with the oscillating movement of the member 59, the members 40 and, therefore, the needle bars 41 will be given a movement in a closed path, it being understood that the rotation of the multi-throw crank shaft 33 and the shaft 51 are so proportioned as to have a complete oscillatory movement given to the member 59 for each complete reciprocating motion given to the wrist pins 38. Also the speed of travel of the base fabric 90, to which it is desired to needle the fibres of the web or bat, is equal to the transverse speed of the needle bar caused by the member 59. The needles carried by the needle bar, therefore, enter the base fabric carrying the fibres of the bat or web therewith and move along with the base fabric during the entering and retracting movement, this being accomplished without drag on either the part of the needles or the base fabric. The base fabric 90 is fed through the machine by any suitable feeding device, such as indicated at 91 in Fig. 3, this feeding device moving the base fabric in a plane transversely to the movement of the banks of needles 67.

Referring now to Figs. 6 to 13 inclusive, there are shown on 42, two needle carriers, each of which comprises a plate 65 equal in length to the needle bar 41 and being provided on its lower end with a recessed portion 66, in which is placed a plurality of parallelly arranged needles 67. Associated with each plate 65 is a cover plate 68 to the lower inner face of which is attached by screws 69 a plate 70, the inner surface of this plate 70 being provided with a plurality of parallelly arranged vertical grooves or serrations 71, in which fits the shank of the needles 67 and which grooves or serrations 71 serve to ac-

curately position and hold the needles. One of the plates 68, as for example the right hand plate shown in Figs. 8 and 9, has secured thereto by riveting, or in any other suitable manner, shafts 72, which shafts pass through as a sliding fit alined perforations in the plates 65, the web 42 and the other plate 68, such shafts 72 being provided at the end remote from the first said plate 68, with an annular recess 73 for a purpose to be herein-after described. The plates 68 are attached to the plates 65 by bolts 74.

The plates 65 on the left-hand side of the web 42, as viewed in Figs. 8 and 9, are identical with the plates 65 on the right-hand side thereof, as are also the plates 68 carrying the serrated member 70 and in this instance also such serrated member 70 is attached to the plate 68 by screws 69. Also this plate 68 is attached to the plate 65 by bolts 74. Associated with the left-hand plate 68, however, is a plate 75, the ends of which are arranged at right angles to the main portion thereof, as indicated at 76. This plate 75 is provided with a plurality of slots 77 which engage with screws 78 that are screwed into the plates 68 and which screws limit the movement of plates 75 longitudinally with respect to the plates 68. This plate 75 is also provided with slots or perforations 79 that act as clearance spaces for the heads of the bolts 74. Also the plate 75 is provided with a plurality of alined perforations 80, large enough at one end to clear the main body of the shaft 72 and small enough at the other end to engage with the annular recess 73, of such shafts 72. Further, the metal surrounding the reduced end of the slot 80 is tapered, as shown at 81, and which acts when the plate 75 is moved from right to left, as viewed in Figs. 6, 7 and 10, to exert a pulling strain on the bolts 72 and, therefore, this mechanism acts as a means for rigidly clamping both the needle bar assemblies onto the web 42. The plate 75 is also provided with a slot 82, through which passes as a sliding fit a stud 83 screwed into the left-hand plate 68, as viewed in Figs. 8 and 9. The outer end of this stud 83 is threaded at 84 to receive a lock nut 85 and which may be utilized to clamp the plate 75 in adjusted position on the plate 68. The needles 67 on the left-hand assembly of the needle carrier are so arranged with respect to the needles 67 on the right-hand needle carrier as to be in staggered relation therewith so that if the needles 67 on the carriers are arranged $1/8$ " apart, such assemblage of needles will produce a needling operation in which the fibres will be needled into and through the base fabric on lines spaced $1/16$ " apart, as is clearly shown in Fig. 7. Each of the needle bars 41 has attached at each end thereof by screws 86, plates 87, which, in the assembled machine engage each other and tend to allow sliding movement between the 130

various needle bars 41, as will be obvious from an inspection of Fig. 2.

The operation of my improved machine is as follows, it being assumed that the machine has been constructed as above described, and that a suitable base fabric is being fed transversely of the reciprocatory motion of the needles 67. Under these conditions and assuming further that on the base fabric is placed a web of fleece or a plurality of superimposed webs of fleeces, and that such base fabric with the superimposed web or webs of fleece thereon is being moved at the proper speed and power being turned into the machine by means of the sprocket 48 from any suitable source of power, the gangs of needles carried by the bars 41 reciprocate in the order and in the manner above described.

Referring to Fig. 2 and assuming that the two other gangs of needles 67 are passing through the base fabric carrying certain of the fibres of the web of fleece therewith, and assuming also that the shaft 51 is rotating at the proper speed, the onward movement of the base fabric and superimposed web of fleece will be matched exactly by the onward movement of the needles 67 caused by the cam roller 60 engaging with the cam race 56, and that after such needles have reached their lowest downward position, that they will be withdrawn by rotation of the crank shaft 33 and will be further carried in synchronism with the base fabric until the needles 67 are clear of the webs of fleece and base fabric.

While I have necessarily shown and described the preferred embodiment of my invention somewhat in detail, it is to be understood that I may vary the size, shape and arrangement of parts within relatively wide limits without departing from the spirit of the invention.

Having thus described my invention, what I claim as new is:

1. An improved needling machine of the kind described, comprising a plurality of banks of needles, said banks being arranged end to end, and means for reciprocating said banks in predetermined groups.

2. An improved needling machine of the kind described, comprising a plurality of banks of needles, said banks being arranged end to end, and means for reciprocating said banks in groups of any desired order.

3. An improved needling machine of the kind described comprising a plurality of banks of needles arranged end to end, and means for reciprocating said banks of needles in a vertical plane in any desired grouping.

4. An improved needling machine of the kind described, comprising a plurality of banks of needles arranged end to end, and means for reciprocating said banks of needles in a vertical plane in any desired grouping, and in any desired order.

5. An improved needling machine of the kind described, comprising a plurality of banks of needles, means for reciprocating said banks, and means for imparting an orbital motion to said bank of needles.

6. An improved needling machine of the kind described comprising a plurality of banks of needles arranged end to end, means for reciprocating predetermined needle banks, and means for feeding a base fabric transversely of the plane of motion of the needles.

7. An improved needling machine of the kind described comprising a plurality of banks of needles arranged end to end, means for reciprocating said banks in predetermined groups, means for feeding a base fabric transversely of the plane of motion of the needles and in synchronism therewith.

8. An improved needling machine of the kind described comprising a plurality of banks of needles arranged end to end, means for reciprocating said banks in groups, and means for feeding a base fabric transversely of the plane of motion of the needles.

9. An improved needling machine of the kind described, comprising a plurality of banks of needles arranged end to end, means for reciprocating said banks in groups of any desired order, and means for feeding a base fabric transversely of the plane of motion of the needles.

10. A needling machine comprising means for feeding a base fabric lengthwise of the machine, a plurality of banks of needles arranged end to end and extending transversely of the machine, and means for reciprocating said banks of needles in groups.

11. A needling machine comprising means for feeding a base fabric lengthwise of the machine, a plurality of banks of needles arranged end to end and extending transversely of the machine, and means for reciprocating said banks of needles in groups, the groups of banks being arranged in balanced relation with respect to each other.

12. A needling machine comprising means for feeding material lengthwise of the machine, a plurality of banks of needles arranged end to end, and running transversely of the machine, means for reciprocating the banks of needles in groups, and means for moving the needles lengthwise of the machine at the same speed of travel as the material and simultaneously with the reciprocation of the needles.

13. A needling machine including a needling element divided into a plurality of separate banks of needles arranged transversely of the machine, and each bank extending over a portion only of the width of the machine, and means for operating said banks successively to cause the needles in one bank to penetrate the fabric to be needled at a dif-
